UNITED STATES PATENT OFFICE.

JOHN I. GUETL, OF BUFFALO, NEW YORK.

SHAFT BEARING.

Application filed January 3, 1921. Serial No. 434,462.

To all whom it may concern:

Be it known that I, JOHN I. GUETL, a citizen of the United States, residing at Buffalo, in the county of Erie and State 5 of New York, have invented new and useful Improvements in Shaft Bearings, of which the following is a specification.

This invention relates to a self-oiling shaft-bearing of the type shown and described in Letters Patent of the United 10 States No. 1,178,231, dated April 4, 1916.

In this patent, the shaft is provided with collars which elevate the oil from the oil-well of the bearing-box to the upper side 15 of the shaft, and one or more saddles which straddle said collars and serve to deflect the oil laterally and spread it over the top of the shaft. If the base of such a saddle is too close to the shaft, the oil is liable to 20 overflow the bearing, while if the saddle is raised too far above the shaft too much oil, escapes under the saddle and the top of the shaft is insufficiently lubricated. To obtain the best results with such a saddle, exactness 25 of construction and nicety of adjustment are required.

The object of my present invention is the provision of a saddle of this kind which while insuring proper lubrication of the 30 shaft and guarding against overflowing, is not dependent for its successful operation upon refinement of construction and adjustment, but permits a certain degree of coarseness without detracting from its efficiency, 35 thus reducing the cost of the device and requiring no special care in applying it to the bearing.

In the accompanying drawings: Figure 1 is a longitudinal central section of a bearing 40 provided with the improvement. Figure 2 is a transverse section thereof on line 2—2, Fig. 1. Figure 3 is an enlarged perspective view of the saddle.

Similar characters of reference indicate 45 corresponding parts throughout the several views.

10 indicates the bearing box having the customary babbitted seat 11 for the shaft 12. The shaft carries the oil-elevating collars or flanges 13 which dip into the oil 50 wells 14 arranged at opposite ends of the shaft-seat 11 and connected by the usual channel 11a. These collars extend through slots 15 and 16 in the top and bottom of 55 the shaft seat, the upper portions of the collars projecting into the usual covered

filling and inspection openings 17 in the top of the bearing box.

Arranged within said filling openings and straddling the adjacent portions of the 60 shaft-collars are the saddles or oil deflectors 18. Each of these saddles consists of a plate, somewhat narrower than the filling opening, having in its lower edge a central notch 19 which receives the companion collar and 65 snugly fits the same to prevent leakage of oil between these parts. As in the saddle of the patent hereinbefore mentioned, the edge of the saddle notch is preferably bounded by a flange 20 which projects beyond the face of the saddle and terminates 70 at its lower ends in feet 21, the toes or front portions of which rest upon the shaft 12. The undersides of these feet are preferably 75 horizontal, or substantially so, as shown, to bring the lower edge of the saddle in close proximity to the shaft.

Above the notch 19, the saddle is provided with an oil relief-passage or opening 22 which extends through the saddle plate 80 and is preferably formed partly in a boss or upward extension 23 of the saddle-flange 20. This opening may be tapered toward the back of the saddle, as shown, to retard the 85 passage of the oil through it.

In practice, each of the saddles rests against the rear wall of the corresponding filling opening 17 with its relief-passage 22 located below said wall and within the main chamber of the bearing box, as shown in 90 Fig. 2.

During the rotation of the shaft, its collars 13 which turn in the direction of the arrow in Fig. 2, elevate the oil in the usual manner. A portion of the oil, encountering 95 the saddle-flange 20 and the body of the saddle, is deflected laterally and passes around the sides of the saddle and returns into one of the wells 14, while another portion of the elevated oil passes through the 100 relief passage 22 of the saddle and flows back into the well.

By this improved construction of the saddle, its base may be placed closely enough to the top of the shaft to properly retard 105 the flow of the oil and insure thorough lubrication of that part of the shaft, while the relief passage allows the surplus oil to escape through it, effectually guarding against overflowing of the bearing-box. This relief 110 opening permits of a more or less inexact construction and fitting of the saddle with-

out sacrifice in the efficiency or reliability of the lubricating devices, and it follows that less time and care are required to produce the saddle, and its cost is correspondingly reduced.

I claim as my invention:

An oil distributing saddle for bearing

boxes, comprising a plate having in its lower edge a notch for receiving an oil-elevating device, and provided in its side between said notch and the upper edge of the plate with a relief-passage extending through the plate.

JOHN I. GUETL.
